COMBINED BUMPER AND GRILLE

Harley J. Earl, Grosse Pointe Farms, Mich., assignor to General Motors Corporation, Detroit, Mich., a corporation of Delaware

Application December 22, 1955, Serial No. 39,454

Term of patent 7 years

(Cl. D14—6)

The broken line portions of an automobile are shown for purposes of illustration only.

I claim:

The ornamental design for a combined bumper and grille, substantially as shown and described.
